CLAIM

The ornamental design for a mini fridge, as shown and described.

DESCRIPTION

FIG. 1 is a perspective view of a mini fridge showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a front elevational view of the mini refrigerator where a light ring disposed on a door of the mini refrigerator is in a configuration of us; and,

FIG. 10 is an enlarged view of portion 10 shown in FIG. 2. The broken lines in the drawings depict portions of the mini fridge that form no part of the claimed design. Dot-dashed broken lines depict light emitting from the light ring that form no part of the claimed design.
